UNITED STATES PATENT OFFICE.

WILLIAM FREDERICK WAMSLEY AND THOMAS McINTOSH, OF WALLA
WALLA, WASHINGTON TERRITORY.

ELECTRICAL CONTACT DEVICE FOR HOSE-COUPLES.

SPECIFICATION forming part of Letters Patent No. 364,558, dated June 7, 1887.

Application filed November 2, 1886. Serial No. 217,796. (No model.)

To all whom it may concern:

Be it known that we, WILLIAM FREDERICK WAMSLEY and THOMAS McINTOSH, citizens of the United States, residing at Walla 5 Walla, in the county of Walla Walla and Territory of Washington, have invented certain new and useful Improvements in Electrical Contact Devices for Hose-Couplers; and we do hereby declare the following to be a full, 10 clear, and exact description of the invention, such as will enable others skilled in the art to which it appertains to make and use the same.

Our invention relates to certain novel improvements in the construction and application 15 of electrical conductors used for lighting and signaling which are applied to the air-brake pipes used on railway-cars, said conductors being so constructed that electrical 20 connections will be established or broken by the act of coupling or uncoupling the pipe-connections, as will be fully understood from the following description when taken in connection with the annexed drawings.

Before describing our invention and improvements, we will state that we are aware 25 that it is not broadly new to utilize the air-brake pipes used on railway-trains and their 30 couplers as a means for bearing electrical connections which are used for lighting and signaling.

In the annexed drawings, Figure 1 is a vertical longitudinal section through two air-brake pipe-couplers, showing our improvements applied thereto. Fig. 2 is a top or face view of one of the couplers used between cars. Fig. 3 is a side elevation of Fig. 2. Fig. 3^a represents a cross-section of the couplers by which the interior disposition of the contact 40 devices is more clearly represented. Fig. 4 is a top view showing the two segments of a contact-ring detached from its coupler. Fig. 5 is a sectional detail showing the electrical points of a pair of couplers in contact. Fig. 6 is a 45 perspective view of a dog used at each end of every car. Fig. 7 is a vertical longitudinal section showing the dog applied to a coupler and completing the circuit through it.

Referring to the annexed drawings by letters, 50 A A designate couplings for flexible pipes or hose B B—such as the ordinary Westinghouse

air-brake hose-coupling—adapted for conducting compressed air by which railway-car brakes are operated. The couplings A are all alike in construction, for which reason a description of one coupling will apply to all of them.

C designates the tubular shank of a coupling, which is adapted to receive and have secured to it air tight a flexible hose, B. This 60 tubular shank C has formed on one end a hollow shell, D, the circular opening in which has an internally-screw-threaded flange or rim, a, adapted to receive a screw-threaded cap, E, hereinafter referred to. The opposite 65 circular opening through the shell D has seated upon a flange, b, surrounding this opening, a circular gasket, c, which is preferably made of vulcanized india-rubber, with an annular rim, c', extending beyond the coupling surface d of 70 the shell, as clearly shown in Fig. 3, and designed to afford, in combination with a similarly-formed gasket on another coupling, an air-tight joint between two connected 75 couplings, as shown in Fig. 1. This gasket-ring c also affords an insulated seat inside of the shell D for two metallic contact-points, F F. These contact-points, which are preferably of brass or copper, are constructed with internal offsets, e e, which, when the contacts are fixed 80 in proper position in the shell, are diametrically opposite each other.

Surrounding the contact-points F F is an insulating-ring, g, having teats g' g' formed on it, which lie between the separated ends of said 85 contact-points and insulate them from each other at these points. If desired, the insulated ring g may form an integral part of the insulator gasket-ring c. It will thus be seen that both 90 of the contact-points F F are electrically insulated from the coupling A, and also that each point is electrically insulated from the other. On the backs of these points, or on those flat surfaces opposite the offsets e e, we apply a ring 95 or washer, h, which may be of leather, hard rubber, or other suitable substance, and when the cap E is forcibly screwed home the prongs f on this cap will bear on the ring h and press the contact-points and gasket firmly into their seat and form an air-tight joint.

The electrical conducting-wires G G, representing the negative and positive poles of an

electric battery, are electrically connected to the respective offsets *e e* of the insulated contact-points *F F* by passing the ends of these wires through holes made through the said offsets, as shown in the drawings.

On the end of the shell *D* is formed a segmental lug, *H*, having a rib, *i*, on one side, which, in the act of coupling two of the shells, engages with a segmental lug, *H'*, formed on the shell and provided with a lug, *i'*. These lugs are concentric to the vertical axis of the shell, so that a coupling is effected by applying two shells together with their faces in juxtaposition and moving them about said axis until the ends of the lugs contact with vertical stops, *k k*, in which position the annular protruding rims *c' c'* of the two gaskets *e e* will be compressed to form a hermetically-tight joint, and the negative and positive offsets *e e* of the electrical contacts *F F* of both shells may register with each other. Now, it will be seen by reference to Fig. 5 that we employ two non-conducting buttons, *J J*, having rounded ends between the said offsets *e e*, which are respectively secured to an opposing electrical point, and each button armed with a spring-needle or point, *l*, extending to the opposite offset—that is to say, each needle *l* is secured to one offset *e* and extends to the opposite offset *e* of its shell or coupling. When the couplers are detached and pressure removed from the buttons, the springs *l* will complete the circuit, when the shells are uncoupled or divided. When the shells are coupled, the circuit is completed between cars by the contact of the offsets *e e* of each coupling. The circuit is completed at the rear end of the last car of a train by means of the dog *K*, (shown in Figs. 6 and 7,) which consists of a perforated shank, *m*, having a flat horizontal plate, *m'*, provided with a metallic button-shaped circuit-closer, *n*, a coupling-hook, *p*, and a stop-lug, *r*. The dog *K* is applied to a coupling by adjusting the dog at right angles thereto, the plate *m'* and its contact-plate being held over the offsets *e e* and flange *c'*. The dog is then forcibly brought around into line with the coupling until the lug *r* strikes the side of the same. The hook *p* engages with the flange of the screw-cap and the circuit-closer *n* contacts with the two offsets *e e*. The dog may be suitably insulated from the car, or the circuit-closer *n* insulated from the dog.

If desirable, buttons above described may be substituted for the dog for closing the circuit at the rear end of a train. The conducting-wires may be disposed of through the tube in any preferred ordinary manner.

Having described our invention, we claim—

1. In air-brake hose-couplers, the combination of the segmental contact-points, their offsets and wire-connections, the ring surrounding said points and insulating them from each other at the ends, and circuit-closers, which automatically complete the circuit when two couplers are disconnected, as described.

2. In air-brake hose-couplers, the combination of the segmental contact-points, the insulator-ring surrounding said points and insulating them from each other at the ends, the packing insulator-ring *e*, formed as described, the washer or ring *h*, and the removable screw-cap having prongs for bearing against this washer, substantially as set forth and shown.

3. In air-brake hose-couplers, the combination of the insulated segmental contact-points, a packing, and spring-actuated circuit-closers attached oppositely to said points, substantially as described.

4. In air-brake hose-couplers, the combination of the segmental points *F F*, having contact-offsets to which the electrical wires are connected, the non-conducting ring surrounding said points and insulating them from each other, and the springs secured to the offsets of the points having non-conducting buttons and automatically completing the circuit when two couplers are disconnected, substantially as described.

5. The combination, with an air-brake hose-coupler constructed as described, and having internal flange, *b*, of the packing ring or gasket *e*, seated on such flange, and having rim *c'*, the segmental points *F F*, having contact-offsets, the insulator-ring *g*, surrounding said points and provided with teats *g'*, which separate their ends, and wires attached to the contact-offsets, adapted for connection with an electric generator, substantially as described.

6. The combination, with an air-brake hose-coupler, *A*, provided with the segmental points *F F*, having contact-offsets and a packing, and a ring surrounding said points and insulating them from each other, of the dog *K*, constructed with the coupling-hook and stop, and provided with a circuit-closing plate, substantially as described.

In testimony whereof we affix our signatures in presence of two witnesses.

WILLIAM FREDERICK WAMSLEY.
THOMAS MCINTOSH.
